United States Patent Office.

NELSON C. BURNAP, OF ARGUSVILLE, NEW YORK.

Letters Patent No. 97,873, dated December 14, 1869.

IMPROVED DINNER-PAIL.

The Schedule referred to in these Letters Patent and making part of the same:

To all whom it may concern:

Be it known that I, NELSON C. BURNAP, of Argusville, in the county of Schoharie, and in the State of New York, have invented a new and improved Dinner-Pail; and do hereby declare that the following description, taken in connection with the accompanying plate of drawings, hereinafter referred to, forms a full and exact specification of the same, wherein I have set forth the nature and principles of my said improvement, by which my invention may be distinguished from others of a similar class, together with such parts as I claim, and desire to secure by Letters Patent.

The nature of my invention consists in constructing a dinner or lunch-pail, with a receptacle for the reception of either hot or cold fluids, as may be desirable, and in the arrangement of the parts of the device so constructed.

In the accompanying plate of drawings, which illustrates my invention, and forms a part of the specification thereof—

Figure 1 is a perspective view, showing the exterior of the device.

Figure 2 is a vertical section, illustrating the interior of the same.

The construction of my invention is as follows, to wit:

Cylindrical metallic bucket A, of the form in common use, provided with the ordinary form of handle B.

Within the said bucket, and at a short distance from the bottom thereof, is soldered, or otherwise secured, the circular disk c.

At the centre of the said disk, is the aperture D, to the edges of which is soldered, or otherwise secured, the upright hollow cylinder E, which is so constructed as to extend a few inches above the cover F, in order

that it may form a lodging-place for the cup, the said cover being provided with an aperture at its centre, through which the said cylinder passes.

By this construction, it is apparent that the bucket is divided into two separate compartments, to wit, an inner reservoir, designed to be used for the reception of liquids or ice, and an outer receptacle, for edibles.

A stop-cock, I, is secured to the pail, near the bottom thereof, in such a manner as to communicate with the inner reservoir.

The operation of my invention is as follows, to wit:

Any hot beverage, as coffee, chocolate, &c., having been poured into the inner reservoir, through the aperture at the top of the cylinder E, the outer receptacle is filled with edibles, and the cup H fitted over the top of the cylinder E, to prevent the escape of the aroma. The edibles placed in the outer receptacle are not only kept warm, but act as non-conductors, to prevent the radiation of heat from the fluid.

If it is desirable to keep the edibles cold, and at the same time secure a supply of cold water, the inner reservoir is filled with ice.

Having thus described the nature, construction, and operation of my invention, I will indicate what I claim as new; and desire to secure by Letters Patent, in the following clause:

I claim the arrangement of the cover F, pail A, cylinder E, disk c, and stop-cock I, when constructed to operate as described.

In testimony that I claim the foregoing, I have hereunto set my hand, this 28th day of September, 1869.

NELSON C. BURNAP.
